UNITED STATES PATENT OFFICE.

PAULINE HANSEN AND WALTER E. J. HANSEN, OF WATTS, CALIFORNIA.

KNIFE.

Application filed January 6, 1923. Serial No. 611,026.

To all whom it may concern:

Be it known that we, PAULINE HANSEN and WALTER E. J. HANSEN, citizens of the United States, residing at Watts, in the 5 county of Los Angeles and State of California, have invented certain new and useful Improvements in Knives, of which the following is a specification, reference being had to the accompanying drawings.

10 This invention relates to certain improvements in knives and it is an object of the invention to provide a novel and improved device of this general character which may be readily applied to the digit of a hand and 15 in a manner to be in position for use and at the same time offering no undue hindrance or obstruction to the use of the hand for other purposes.

It is also an object of the invention to provide 20 a novel and improved device of this general character which is particularly adapted to be applied to the thumb of the hand and which is especially designed for use in preparing various kinds of fruits, 25 vegetables and the like for the table or for canning.

The invention consists in the details of construction and in the combination and arrangement of the several parts of our improved 30 knife whereby certain important advantages are attained and the device rendered simpler, less expensive and otherwise more convenient and advantageous for use, as will be hereinafter more fully set forth.

35 The novel features of our invention will hereinafter be definitely claimed.

In order that our invention may be the better understood, we will now proceed to describe the same with reference to the accompanying 40 drawings, wherein:

Figure 1 is a view in perspective illustrating a knife constructed in accordance with an embodiment of our invention and in applied position; and

45 Figure 2 is a view in top plan of the knife as illustrated in Figure 1.

As herein disclosed, our improved knife comprises a body plate 1 arcuate in cross section and which has its outer end portion 2 pointed. The inner end portion of the body 1 at opposite sides thereof is provided with the arcuate arms 3 possessing a certain degree of inherent resiliency and which terminate in the upstanding wings 4, said 50 wings 4 being in outward diverging relation as is clearly illustrated in the accompany-

ing drawings and which serve to facilitate the application of the knife to the digit, such as the thumb, of the hand. One longitudinal marginal portion of the body 1 between an arm 3 and the pointed portion 2 is provided with an angularly related cutting blade 5 preferably integrally formed therewith. The opposite marginal portion of the body 1 immediately adjacent to the pointed portion 2 is provided with the curved resilient arm 6 overlying the body 1 and having its inner corner of its free end portion disposed slightly outward as indicated at 7 to further facilitate the application of the device into working position.

As is clearly illustrated in the accompanying drawings, our improved knife is especially designed for use in connection with the thumb of a hand and when so applied the ball of the thumb is received within the concave face of the body 1 with the arms 3 straddling the thumb from below inwardly of the first knuckle and with the arms 6 overlying the thumb outwardly of the first knuckle. By this arrangement the knife is effectively maintained in applied position and with the blade 5 disposed along the outer side of the thumb and in which position the blade 5 is in a convenient position for such usage as may be necessary in preparing fruits, vegetables or the like for the table or for canning. It will also be readily understood that with our improved knife applied only to the thumb, the remaining digits or fingers of the hand are left free and unobstructed for the requisite handling of the articles.

The knife in its entirety is of such size as to have the pointed portion 2 of the body to extend beyond the outer end of the thumb so that this end portion can be used for removing eyes or for other purposes desired.

By having the arms 3 and 6 resilient it will be readily understood that the knife in its entirety will adjust itself to thumbs of different sizes.

From the foregoing description it is thought to be obvious that a knife constructed in accordance with our invention is particularly well adapted for use by reason of the convenience and facility with which it may be assembled and operated, and it will also be obvious that our invention is susceptible of some change and modification without departing from the principles and spirit thereof and for this reason we do

not wish to be understood as limiting ourselves to the precise arrangement and formation of the several parts herein shown in carrying out our invention in practice except as hereinafter claimed.

We claim:

A knife of the class described comprising an elongated body arcuate in cross section, one end portion of said body at opposite sides thereof having arcuately disposed arms terminating in outstanding wings, said wings being in outward diverging relation, a longitudinal marginal portion of the body out-

wardly of one of the arms being provided with an angularly related cutting blade, the opposite marginal portion of the body adjacent to the end thereof remote from the arcuate arms being provided with an inwardly curved resilient arm overlying the body and having the inner corner of its free end portion disposed slightly outward.

In testimony whereof we hereunto affix our signatures.

PAULINE HANSEN.
WALTER E. J. HANSEN.
